UNITED STATES PATENT OFFICE.

JOHN W. DWIGGINS, OF MUNCIE, INDIANA, ASSIGNOR TO RICHARD H. SCHWEITZER,
OF KNIGHTSTOWN, INDIANA.

WIRE-FENCE LOOM.

Application filed June 26, 1922. Serial No. 571,077.

To all whom it may concern:

Be it known that I, JOHN W. DWIGGINS, a citizen of the United States, residing at Muncie, in the county of Delaware and 5 State of Indiana, have invented a new and useful Wire-Fence Loom, of which the following is a specification.

My invention relates to wire fabric making machines and has particular reference 10 to that type of machine wherein the crossing strands of the fabric are tied together by means of a tie generally taking the form of a staple before it is bent to tying position.

15 One of the objects of my invention is to provide a means for feeding the staples to the tying mechanism positively and in timed relation to the operation of the dies.

Another object of my invention is to so 20 co-relate the forming fabric and the dies that the forming fabric, when the dies are opened, shall be free from the dies and readily accessible at the stapling or tying points; such that the staples may be readily and 25 accurately delivered to the dies; and such that the dies will be accurately co-related preliminary to the driving of the tying staple.

For the purpose of illustrating my invention I have shown one embodiment there- 30 of in the accompanying drawings, in which:

Fig. 1 is a side elevation of one set of dies for tying the staples, the feeding means therefor being shown in operative position;

35 Fig. 2 is an enlarged detail view of the feeding mechanism, parts of the same being shown in section;

Fig. 3 is a sectional view taken on the line 3—3 of Fig. 2;

40 Fig. 4 is an enlarged detail view showing the means for moving the staple off the feeding member;

Fig. 5 is a sectional view on the line 5—5 of Fig. 2; and

45 Fig. 6 is a detail sectional view showing the manner of supporting the staple on the feeding member.

In this type of machine there is generally provided a plurality of sets of dies 50 between which the longitudinal strands of the fabric are advanced, and between which are arranged to be positioned the transverse strands of the fabric. After the transverse strands have been positioned, the sets of

dies are operated to tie the strands together 55 by means of a staple or wire tie. In the structure illustrated I have shown only one set of dies as the sets are all duplicates.

In Fig. 1 the stationary cross beam 1 of the machine supports a die carrier 2 which 60 at its lower end is provided with one of the dies 3 for bending the tie staple. Cooperating with the die 3 is a second die 4 which is mounted upon a reciprocating cross head 5. The die 4 is provided with an upwardly 65 extending finger 6, the inner face 7 of which is tapered to cooperate with a face 8 of the upper die so that as the lower die is raised to cooperate with the upper die the two dies will be properly aligned. 70

Formed in the front face of the die support 2 is an elongated channel or groove 9 which forms a feed chute for the staple. This groove extends clear to the bottom of the supporting member and at its lower 75 end cooperates with the rear face of the die 3. Operating within this groove is a plunger 10 which forces the tie down to the bottom of the groove and holds it at the lower end until it has been tied by the 80 dies 3 and 4. This plunger is supported from a vertically reciprocating bar or cross head 11 mounted in the general framework of the machine.

For feeding the ties to the chute 9 I provide a rotary die carrier 12 arranged between the inclined feed runway 13 and the groove 9. This carrier 12 comprises a disk having a plurality of transverse notches 12^a in its periphery to receive the tie. The 85 disk is suitably supported for rotation upon an axle 14 which is journaled in outwardly extending arms 15 mounted on the member 2. The axle 14 is rotated by a dog 16 adapted to engage the teeth of a ratchet 17 mounted on the axle 14, the dog in turn being mounted on an arm 18 extending from a collar loosely journaled on the axle 14 and connected by an operating rod 19 with the reciprocating head 11. 95

For kicking the ties out of the notches 12^a and into the groove 9 I provide a bifurcated kick off, the two arms 20 of which straddle the disk 12 and which is pivoted at 21 on the supporting member 2 immediately above the 100 die 3. The arms are urged into an outward position by means of a spring 22 secured to the support for the kick off and having its 105

free end engaging a pin 23 on one of the arms 20. The rear faces of the free ends of the arms 22 have formed thereon cam surfaces 24 which are adapted to be engaged by transversely extending pins 25 on the disk. These pins 25 are so spaced on the disk with relation to the notches 12^a that they will advance the arms 20 to move the staple out of the notch when the notch reaches a point immediately opposite the channel 9.

The tie staples vary in width slightly and in order to insure that all of the staples will be sufficiently narrow to operate in the channel or groove 9 I provide a gauging die 26 having a pair of arms which straddle the disk 12 in the path of the staples as they are advanced from the inclined runway 13 to the channel 9. These arms are spaced apart a distance equal to or somewhat less than the width of the channel 9 and as the staples pass between the arms such staples as are too wide to freely operate in the channel 9 have their prongs squeezed together so that the width of the staples will be correct. The die 26 is preferably mounted on an arcuate arm 27 supported from the stationary member 2.

In operation, the staples are mounted upon the inclined delivery member 13, the lower end of which is substantially horizontal and in proximity to the periphery of the disk 12. As the head 11 moves upwardly the dog 16, engaging in a tooth of the ratchet 17, rotates the disk 12 in a clockwise direction and as one of the notches 12^a moved upwardly a staple moves off the end of the runway 3, under the weight of the staples behind it, and into one of the notches 12^a. The disk is advanced step by step by the reciprocation of the head 11 and as the staple passes upwardly on the disk 12 it passes between the two arms 26 which properly gauge the width of the staple which is finally advanced to a position opposite the groove 9. As the disk continues to rotate a pair of pins 25 engage the cam faces 24 of the arms 20 and force these arms forwardly. In their forward movement the arms engage the staple in the notch 12 of the disk, and move the staple out of this notch and into the channel 9, the staple dropping by gravity towards the bottom of the channel and being held against dropping out of the channel by the end 28 of a retaining spring 29 secured in a groove formed in the rear face of the channel 9. During the rotation of the disk 12 the plunger 10 is descending and the tie is forced downwardly in the die 3 until it is engaged by the upwardly moving die 4 and its ends bent around the wires of the fabric.

It will be noted that, contrary to the usual practice, the line of action of the dies is not at right angles to the normal plane of the forming fabric, but, instead, is at a substantial angle thereto. However the line of ac-

tion of the dies is substantially vertical so that whatever gravity effect there may be on the staples will facilitate the co-action of the staples with the feeding and driving mechanism, the normal plane of the forming fabric being practically 45° from the vertical while the provision of the coacting tapered surfaces 7-8, insure an accurate co-relation of the dies.

As previously stated, die 3 is stationary and die 4 is reciprocable. The normal plane of the fabric, due to the tension in wire 30, as it passes over the supporting rolls 31 and 32 is somewhat below the lower face of die 3 and in order to insure against sticking of the freshly formed tie in the upper die, the lower die 4 is provided with a pin or finger 33 projected above the adjacent wire 30.

By arranging the line of co-action of the dies vertically, I am able to get the most convenient arrangement of driving mechanism and to get the gravity effects on the staples in the most convenient way, and by arranging the forming fabric at an upwardly and rearwardly inclined angle, I am able to obtain ready access to the parts. The faces of the dies must, of course, be at a corresponding angle to the line of reciprocation of the die 4 and, therefore, the inclined co-acting faces 7-8, closely approximating the line of reciprocation of die 4, become important for the purpose of definitely assuring the proper association of the dies during the period of tie drive.

I claim as my invention

1. In a wire fabric machine, the combination with tie bending dies having a delivery chute leading thereto, of means for delivering staple ties to said chute comprising a rotary member having notches in its periphery to receive the base of the staples, the legs of the staples being arranged to straddle said member, said member during a portion of its rotation being arranged to pass through said die chute, a pair of arms straddling said member and means for moving said arms to force the staples out of the notches as the member rotates through said chute.

2. In a wire fabric machine, the combination with staple tie bending dies, of means for feeding the ties to said die including a rotary member arranged to receive said ties and deliver the ties to the dies, and a gauging die for said ties in the path of the same prior to their delivery to the bending dies.

3. In a wire fabric machine, the combination with tie bending dies, of means for feeding ties to said dies including a rotary member arranged to receive said ties from a feeding member and deliver them to the dies, and a gauging die interposed in the path of travel of said ties and through which the ties are passed by said rotary member.

4. In a wire fabric machine, the combination with tie bending dies having a tie chute leading thereto, of a gravity fed tie delivery chute associated therewith, a rotary member interposed between said delivery chute and die chute and having tie receiving notches in its periphery to receive the ties from said delivery chute, means for removing the ties from said notches as said member passes through the die chute, and a gauging die in the path of travel of said ties as they pass from the delivery chute to the die chute.

5. In a wire fabric machine, the combination with tie bending dies having a delivery chute leading thereto, of a tie feeding member comprising a rotary disk having tie receiving notches on its periphery, said disk during a portion of its rotation being arranged to pass through said tie chute, a pair of arms straddling said disk, means for operating said arm to force the ties out of said notches as the disk passes through said chute, and a gauging die associated with said disk and through which the ties are passed by the rotation of said disk prior to their delivery to the die chute.

6. In a wire fabric machine, the combination with a pair of co-acting tie forming dies movable one with relation to the other and having their co-acting faces set at an acute angle to the line of movement, tie feeding and driving means associated with said dies and means for supporting the fabric running wire between the dies and at an acute angle to the line of relative movement of the dies.

7. In a wire fabric machine, the combination of a pair of co-acting tie forming dies movable one with relation to the other and having their co-active faces set at an acute angle to the line of movement, said dies being provided with co-acting guide faces set at a slight angle to the line of movement to form with the die faces a positioning crotch, tie feeding and driving means associated with said dies, and means for supporting the fabric running wire between the dies

and at an acute angle to the line of relative movement of the dies.

8. In a wire fabric machine, the combination of a pair of co-active tie forming dies movable one with relation to the other upon a substantial vertical line and having their co-active faces set at an acute angle to the vertical, tie feeding and driving means associated with said dies, means for supporting the fabric running wire between the dies at an acute angle to the vertical, and means carried by the moving die for overlaying the associated running wire to pull it from the associated die.

9. In a wire fabric machine, the combination of a pair of co-acting tie forming dies movable one with relation to the other upon a substantially vertical line and having their co-acting faces set at an acute angle to the vertical, said dies being provided with co-acting guide faces set at a slight angle from the vertical to form with the die faces a positioning crotch, tie feeding and driving means associated with said dies, means for supporting the fabric running wire between the dies at an acute angle to the vertical, and means carried by the moving die for overlaying the associated running wire to pull it from the associated die.

10. In a wire fabric machine, the combination of a pair of co-acting tie forming dies movable one with relation to the other and having their co-acting faces set at an acute angle to the line of movement, tie feeding and driving means associated with said dies, and means for supporting the fabric running wire between the dies and at an acute angle to the line of relative movement of the dies, the meeting point of the dies being above the normal plane of the running wire.

In witness whereof, I, JOHN W. DWIGGINS have hereunto set my hand at Indianapolis, Indiana, this 12th day of June, A. D. one thousand nine hundred and twenty two.

JOHN W. DWIGGINS.
